Primary Examiner — Charles D Hanson*(74) Attorney, Agent, or Firm* — Fitch, Even, Tabin & Flannery LLP(57) **CLAIM**

The ornamental design for a bone plate, as shown and described.

DESCRIPTION

FIG. 1 is a top perspective view in accordance with a first embodiment of my new design;

FIG. 2 is a bottom perspective view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front elevational view thereof; and,

FIG. 8 is a rear elevational view thereof.

The broken lines depict unclaimed environmental subject matter and form no part of the claimed design.

It is contemplated that other embodiments of the design may include any part, portion, element, or any combination thereof shown in the figures. It is specifically contemplated that any and all solid lines and portions thereof may be converted to broken lines, whether in a subsequent divisional or continuation application and/or by amendment.
